UNITED STATES PATENT OFFICE.

EDWARD JOSLIN KINGSBURY, OF KEENE, NEW HAMPSHIRE.

AUTOMATIC DRILLING MACHINE.

Application filed January 22, 1921. Serial No. 439,161.

My invention relates to new and useful improvements in automatic drilling machines.

An object of the invention is to provide a drilling machine of this character, in which a predetermined positive feed of the drill spindle is dispensed with and a yielding means is employed to impart the forward thrust to the drill spindle, whereby the drill will not be broken, as might be the case where there is a positive forward feed of the drill spindle.

Another object of my invention is to maintain an even and steady pressure on the drill under normal working conditions, whether the work operated upon is soft or hard, or has a portion thereof harder than another, as well as prevent the rapid forward movement of the drill spindle when it breaks through the work and to provide an automatic means for stopping the feeding of the drill spindle forward and return it to its normal starting position when the drill has become dull and is not cutting efficiently after drilling a predetermined length of time.

A still further object of my invention is to provide a machine of this character which is simple in structure and durable and having certain details of structure and combination of parts hereinafter more fully described.

In the accompanying drawings—

Figure 1 is a side view, partly in section, of my improved drilling machine;

Figure 2 is a top plan view of Figure 1, with the drill spindle drive pulley and its connection removed;

Figure 3 is an enlarged end view of Figure 1, looking from the rear;

Figure 4 is a transverse vertical sectional view taken on the line 4—4 of Figure 1, looking in the direction of the arrow;

Figure 5 is a transverse horizontal sectional view taken on the line 5—5 of Figure 1 and looking in the direction of the arrow.

Referring now to the drawings, 1 represents the base of my improved drilling machine, which is preferably of cast metal and has at each end upwardly extending standards 2 and 3. The standard 2 is provided at its upper end with a cylindrical bearing 4 in which the drill spindle 5 is rotatably mounted and is adapted to move longitudinally. The standard 3 is extended rearwardly, as indicated at 6, and is provided

with a cylindrical bearing 7, in which the rear end of the drill spindle 5 is rotatably and longitudinally mounted, as will be hereinafter more fully described.

The drill spindle 5 is provided with a pulley 8, over which the drive belt 9 passes and by means of which the drill spindle is rotated. This pulley, as shown, is of a flat elongated form, which allows the free longitudinal movement of the drill spindle without providing for the transverse movement of the belt. Said pulley is of a hollow form and has secured therein a forwardly extending arm 10 which remains stationary against rotation, as will be fully understood by reference to my Patent No. 1,379,765, dated May 31, 1921, and, therefore, needs no further description.

The standards 2 and 3, a short distance above the base, are provided with bearings 11 and 12. Mounted in the bearing 12, is a sleeve 13, in which is rotatably supported the shaft 13', which extends forward and has its forward end rotatably mounted in the bearing 11. Rigidly carried by the shaft 13' is a cam 14, having at its forward end a cam surface 15 and against which bears the roller 16 carried by the intermediately pivoted lever 18. This lever, as shown, is pivoted at 19 to the rearward extension 19', carried by the standard 2, and has its upper end pivoted at 22 to the block 23 carried by the arm 10. The block is adjustably connected to the arm 10 by a set screw 24 so as to adjust the lever 18 and bring the roller 16 against the cam 14.

The sleeve 13, beyond the bearing 12, is provided with a worm 24', for the purpose hereinafter described. Beyond the worm 24' is a worm gear 25, meshing with the worm 26 transversely mounted in the base and driven by a pulley 27, over which the belt 28, passes. The belt is continuously driven by the same mechanism which drives the belt 9 and is timed therewith. The worm gear 25 is of a hollow form and has a conical face 29 which forms one portion of the cone clutch. The cam 14 has a rearwardly extending portion 30 and has a cone face 31 which enters the face 29 so that the cam is driven with the worm 25, but allows a slipping action between the same when the pressure of the roller 16 is not sufficient to lock the same together, as will be later more fully described.

The lever 18, on one side of the extension

20, is provided with a forwardly extending arm 32 which has an eye in its forward end and in which is secured a cable 33, carrying a weight 34, by means of which the lever 5 18 is normally held forward for feeding the drill spindle forward and is held against too rapid forward movement by the engagement of the roller 16 with the cam 14. This lever 18 extends some distance beyond the 10 roller 16, as indicated at 35 and is engaged by the hooked end 36 of the L-shaped catch 37. This catch is normally held in an upward position by the spring 38, so as to catch under the end 35 of the lever 18 and 15 thus prevent the forward feed of the drill spindle, as will be hereinafter more fully set forth.

As heretofore described, the sleeve 13 is continuously rotated by the worm 26 meshing with the worm gear 25 and when the 20 drill spindle travels forward sufficiently to allow the weight 34 to exert enough pressure on the lever 18 and force the cam 14 and its cone portion into engagement with the cone face of the worm gear 25, there is 25 a locking action between the cam and the worm which causes a slow rotation of the cam. It is not necessarily a positive locking clutch action between the cam and worm gear 30 as there would normally be a slipping action to allow a gradual slow rotation of the cam to permit the feed of the drill. By this structure, it will be seen that, upon the drill breaking through the work, there will not be 35 a rapid forward movement and thus prevent any injury to the drill.

Mounted in the bearing 35', in the base 1, 40 is a rock shaft 36' which is below the sleeve 13 but parallel therewith and adapted to oscillate in said bearing. Said shaft 36', beyond the bearing 35, is of a rectangular form and has slidably mounted thereon the sleeve 37' which is normally held against the collar 39 by means of a coil spring 40, 45 as shown in Figure 1 of the drawings. This sleeve 37' is provided at one side with an upwardly extending arm 41 which has an inwardly turned end 41' meshing with the worm 24' so that the sleeve is caused to travel 50 on the shaft 36' as the worm 24' is rotated. The shaft 36' is not only mounted in the bearing 35' to oscillate, but also has longitudinal movement so that when the sleeve 37' has travelled on the shaft, caused by 55 the engagement of the arm 41' with the worm, and engages the shoulder 42, the shaft is moved longitudinally for the purpose hereinafter described.

The rear end of the shaft 36' is supported 60 in the lower end of the lever 43 at 44. The lever 43 is yoke shape, as shown in Figure 3, and its upper end straddles the standard 2 and is pivoted thereto at 45. Pivoted to the lever 43 at 46 is a link 47, 65 which extends forward and is pivotally con-

nected at 48 to the latch 49. The latch 49 is pivoted to the base 1 at 50 and a spring 50' normally holds or forces the same forward, as shown in Figure 1 of the drawings, so that the upper end extends over the lower 70 end of the latch member 37 and normally holds the same, as shown in Figure 1.

The shaft 36' has a collar 51 secured thereto, on the inside of the lever 43 and a spring 52 is interposed between the collar and lever, 75 so that there is a yielding pressure exerted on the lever. The shaft 36', beyond the lever, is provided with a weighted collar 53, secured against movement, and having an outwardly extending arm 54 and a hooked end 55 extending in the path of the cam 56, carried by the shaft 13', so that, upon the rotation of the shaft 13' (later described) the shaft 36' is rocked so as to throw the member 41' out of engagement with the worm 24' on the sleeve 13, after the shaft 13' has made one rotation, and the spring 40 will return or force the sleeve 37' forward 80 so that the member will be opposite the forward end of the worm. The continued rotation of the shaft 13' brings a portion of the cam 56 opposite the hooked end 55 of the arm 54 so that the shaft 36' will oscillate by the spring tension to again throw the member into engagement with the worm 24' and 85 the drill is ready for another operation. 90

When the drill has completed its operation, the roller 16 carried by the lever 18, is at the bottom of the incline 15 of the cam and in order to give the necessary power to 95 return the roller to the top of the incline and with it the drill, back to its starting point, as well as the weight, ready for another operation, I provide a jaw clutch 100 105 56'. This clutch comprises a collar 57, rigidly carried by the shaft 13 and has a forwardly spring-pressed pin 58 adapted to enter a notch 59 in the end of the sleeve 13, so that the sleeve and shaft are locked together independent of the friction clutch and as the sleeve is positively rotated, the shaft 13' will be rotated carrying the cam around so that the lever 18 and operated parts are returned to their normal starting point with the roller on the top of the incline of the cam. 110 The standard 3 surrounding the shaft 13' is provided with a ring 60 which has a cam face adapted to engage the spring-pressed pin 58 and hold it out of the notch 59; but, upon the rotation of the shaft 13', to bring the roller 16 in the bottom of the incline 15, the spring pin 58 is allowed to enter the notch for coupling the shaft 13' and the sleeve 13 together and the cam carried by the shaft 115 operates the lever 18 to raise the weight and return the drill to its starting point. 120

The yoke 43, on opposite sides, is provided with inwardly projecting pins or lugs 44' and 45', which are adapted to engage the shoulder 57' carried by the collar 57, and 130

normally bears against the same. The rearward movement of the shaft 36' serves a double purpose—first, of throwing the catch 48, and the continued rearward movement of the shaft causes the pins 44' and 45' to engage the shoulder 57' carried by the collar 57 and moves the same rearwardly, thus causing the shaft 13' to move therewith and the cone clutch 25 to be locked to the continuously driven sleeve 13, and through the cam 14 and lever 18 the drill spindle is carried back to the starting point and locked by the latch 49. By this structure, it will be seen that the shaft 13 is revolved independently of the pressure of the roller 16 carried by the lever after the machine has been operating a predetermined length of time.

The operation of the machine is as follows:

The drill spindle 5 is fed forward by the weight 34, and as the drill works its way through the work, the roller 16 causes a greater pressure upon the cam 14, and the cone face thereof frictionally engages the cone face or recess in the worm 25 and thus locks or causes a slight rotation of the cam, so that the cam face is always in contact with the roller to prevent any rapid forward movement of the drill spindle. The sleeve 13' is continuously rotated by means of the worm 26 which causes the sleeve 27 to slide longitudinally upon the shaft 36' by means of the arm 41 meshing with the worm 24'. When the sleeve strikes against the shoulder 42 of the shaft, the same is moved longitudinally, the operation of which will be hereinafter described.

The continued gradual rotation of the sleeve 13 and the feeding of the drill spindle causes the cam 14 to rotate until the member or collar 57 carried thereby is rotated and the spring pressed latch 58 will slide off of the beveled face of the collar 57 carried by the frame and drop into the notch 59 carried by the sleeve, and thus the cam shaft 13' and the sleeve 13 are positively locked together and the cam is rotated to move the lever 18 forward, returning the drill spindle to its starting point by the engagement of the cam with the roller 16. If, however, the drill is not effectively cutting, the sleeve 37' is caused to travel on the shaft and engage the shoulder 42, force the shaft 36' rearwardly and cause the link 47 to trip the catch 49, which releases the lock which also engages the lower end of the lever 18 and holds it against rearward movement. If, however, there is no pressure of the roller 16 upon the cam, owing to the lack of cutting of the drill, the rotation of the sleeve 13 moves the shaft 36' rearwardly and causes the yoke 43 to move rearwardly and carrying the shaft 13' causes the cone clutch 25 to rotate the cam

and move the drill spindle back to its starting point. The rotation of the shaft 13' causes the cam 56 to engage the arm 54 and rock the sleeve 37' on the shaft 36', disengaging the arm 31 from the worm and allowing the spring to return the sleeve to its forward position and after the cam 56 has released the arm 54, the sleeve returns to its normal position with the arm 41 meshing with the worm ready for another operation.

Having thus described my invention, what I claim as new and desire to secure by Letters Patent, is:

1. A drilling machine comprising a rotary drill spindle, yielding means for feeding the drill spindle forward, automatic means for regulating the maximum feed of said drill spindle comprising a cam, a positively driven member having a friction clutch connection with said cam, and an auxiliary means adapted to disengage said friction clutch after the positively driven member has been rotating a predetermined length of time without the drill working effectively.

2. A drilling machine comprising a rotary drill spindle, yielding means for feeding the drill spindle forward, a cam for regulating the maximum feed of said drill spindle, a continuously driven member having a friction clutch connection with said cam and regulated by the forward movement of the drill spindle, and a positive clutch connection between the cam and the continuously rotating member adapted to come into operation after the drill has completed its operation and return the drill spindle to its starting point.

3. A drilling machine comprising a rotary drill spindle, yielding means for feeding the drill spindle forward, a cam for regulating the maximum feed of said drill spindle, a continuously driven member having a friction clutch connection with the cam and controlled by the forward movement of the drill spindle, means for positively locking the cam and the continuously rotating member together after the drill has completed its operation, and an auxiliary means adapted to disengage said friction clutch after the continuously driven member has been operating a predetermined length of time for rotating the cam and returning the drill spindle to the starting point, and means operated by the last mentioned means for locking the drill spindle against forward movement.

4. A drilling machine comprising a rotary drill spindle, yielding means for feeding the drill spindle forward, a cam for regulating the maximum feed of said spindle, a continuously driven member having a friction clutch connection with the cam and controlled by the forward movement of the drill spindle, means for positively locking the cam and the continuously rotating member together after

- 1 the drill has completed its operation, and an auxiliary means adapted to disengage said friction clutch after the continuously driven member has been operating a predetermined length of time for rotating the cam and returning the drill spindle to the starting point, and a latch tripped by the last mentioned means for engaging the feeding means and locking the drill spindle against forward movement.
- 5 5. A drilling machine comprising a rotary longitudinally movable drill spindle, yielding means for feeding the drill spindle forward, a cam loosely supported, a continuously driven member having a friction clutch connection with the cam, an intermediately pivoted lever having one end connected to the drill spindle at its upper end and its lower end bearing against the cam for regulating the maximum feed of said drill spindle, and automatic means for coupling the cam to the continuously driven member after the drill has been operating a predetermined length of time.
- 10 6. A drilling machine comprising a frame, a rotary longitudinally movable drill spindle mounted therein, yielding means for feeding the drill spindle forward, a cam loosely and rotatably mounted in the frame, a positively and continuously driven member adjacent the cam, an intermediately pivoted member carried by the frame and having one end connected to the drill spindle and its opposite end bearing against the cam, a friction clutch connection between the cam and continuously rotated member and controlled by the pressure of the intermediately pivoted member on the cam, and automatic means for coupling the cam to the continuously driven member after the drill has been operating a predetermined length of time.
- 15 7. A drilling machine comprising a frame, a rotary longitudinally movable drill spindle mounted thereon, yielding means for feeding the drill spindle forward, a cam loosely and rotatably mounted in the frame, a positively and continuously driven member adjacent the cam, an intermediately pivoted member carried by the frame and having one end connected to the drill spindle and the opposite end bearing against the cam, a friction clutch connection between the cam and the continuously rotating member and controlled by the pressure of the intermediately pivoted member on the cam, and a positive clutch adapted to lock the cam and the continuously rotating member together for rotating the cam and returning the drill spindle to its starting point after the drill has completed its operation.
- 20 8. A drilling machine comprising a frame, a rotary longitudinally movable drill spindle mounted therein, yielding means for feeding the drill spindle forward, a rotary member mounted in the frame and regulating the maximum feed of the drill spindle, a continuously driven member adapted to drive the rotary member by a friction clutch, and a positive clutch adapted to lock the rotary member together for rotating the rotary member and returning the drill spindle to its starting point after the drill has completed its operation.
- 25 9. A drilling machine comprising a frame, a rotary longitudinally movable drill spindle mounted therein, yielding means for feeding the drill spindle forward, a rotary member mounted in the frame and regulating the maximum feed of the spindle, a continuously driven member adapted to drive the rotary member by a friction clutch, auxiliary means adapted to lock the rotary member and the continuously rotated member together for returning the drill spindle to its starting point after the drill has been rotating a predetermined length of time, and automatic means for locking the drill at its starting point.
- 30 10. A drilling machine comprising a frame, a rotary longitudinally movable drill spindle mounted therein, yielding means for feeding the drill spindle forward, a rotary member mounted in said frame for regulating the maximum feed of the drill spindle, a continuously driven member, a friction clutch connection between the rotary member and the continuously rotated member, an auxiliary means adapted to lock the rotary member and the continuously rotated member together for returning the drill spindle to its starting point after the drill has been rotating a predetermined length of time, and means operated by the rotation of said rotary member for locking the drill in its starting position.
- 35 11. A drilling machine comprising a frame, a rotary longitudinally movable drill spindle mounted therein, yielding means for feeding the drill spindle forward, a rotary member mounted in the frame and adapted to automatically control the maximum forward feed of the drill spindle and to return the drill spindle to its starting point, a clutch for locking the drill spindle in its starting position and means operated by the rotary member for releasing the catch which locks the drill spindle in its starting position.
- 40 12. A drilling machine comprising a frame, a rotary longitudinally movable drill spindle mounted therein, yielding means for feeding the drill spindle forward, automatic means for regulating the feed of the drill spindle, automatic means for returning the drill spindle to the starting point, and automatic means directly operated by the feed regulating means for locking the drill spindle in its starting position.
- 45 13. A drilling machine comprising a frame, a rotary longitudinally movable drill spindle

5 mounted in the frame, yielding means for feeding the drill spindle forward, a rotary cam for regulating the maximum forward feed of the drill spindle, a continuously rotating member, a friction clutch connecting the cam and continuously rotating member together and controlled by the feed of the drill spindle, a worm carried by the continuously rotating member, an arm working in 10 said worm, an auxiliary means for connecting the cam and the continuously rotating member together for returning the drill spindle to its starting point, and means operated by the arm for locking the drill spindle in its returned starting position.

14. A drilling machine comprising a frame, a rotary longitudinally movable drill spindle mounted in the frame, yielding means for feeding the drill spindle forward, 20 a rotary cam for regulating the maximum forward feed of the drill spindle, an intermediately pivoted arm having one end connected to the drill spindle and the opposite end engaging the cam, a continuously rotated 25 member, a friction clutch controlled by the feed of the drill for connecting the cam and the continuously rotated member together, a worm carried by the continuously rotating member, a longitudinally movable member 30 carried by the frame, an arm carried by the member and meshing with the worm for moving the same, and means operated by the movement of said member for releasing a catch for engaging the lower end of the intermediately pivoted member for locking it 35 against movement with the drill spindle in its returned position, and a positive clutch for locking the cam and the continuously rotating member together for returning the drill spindle to the starting point after the drill spindle has completed its operation.

15. A drilling machine comprising a frame, a rotary longitudinally movable drill spindle mounted in the frame, automatic 45 means for regulating the maximum forward feed of the drill spindle, automatic means for returning the drill spindle to the starting point by the automatic means for regu-

lating the maximum forward feed, and automatic means directly controlled by the continued rotation of the drill spindle for locking it in its starting position after the drill has rotated a predetermined length of time.

16. A drilling machine comprising a frame, a rotary longitudinally movable drill spindle mounted in the frame, a rotary cam, an intermediately pivoted arm having one end connected to the drill spindle and the opposite end bearing against the cam, yielding means for moving the upper end of the arm forward for feeding the drill spindle forward, a continuously rotating member, a friction clutch connection between the cam and the continuously rotating member and controlled by the feed of the drill spindle, a positive clutch adapted to lock the cam and the continuously rotating member together for rotating the cam and returning the drill to its starting point after the drill has completed its operation, a worm carried by the continuously rotating member, a shaft below the same, a spring pressed sleeve on the shaft, an arm carried by the sleeve and meshing with the worm, means operated by the sleeve for releasing a latch for engaging the lower end of the intermediately pivoted feed arm for locking the drill spindle in its starting position, and means operated by the rotation of the cam for oscillating the sleeve to throw the arm out of engagement with the worm for returning it to its normal forward position ready for another operation.

17. A drilling machine comprising a rotary drill spindle, yielding means for feeding the same forward, a continuously rotated member, a cam having a yielding friction clutch member connected with the rotating member for controlling the said feed of the drill spindle, a positive means for connecting said controlling cam with said continuously rotating member for returning said cam to its initial position for returning said spindle to its starting point.

In testimony whereof, I affix my signature.

EDWARD JOSLIN KINGSBURY.
